UNITED STATES PATENT OFFICE.

JOHN L. HENRY, OF DALLAS, TEXAS.

WALKING TOY.

Application filed February 23, 1923. Serial No. 620,639.

To all whom it may concern:

Be it known that I, JOHN L. HENRY, a citizen of the United States, residing at Dallas, in the county of Dallas and State 5 of Texas, have invented certain new and useful Improvements in Walking Toys, of which the following is a specification.

This invention relates to new and useful improvements in walking toys.

10 The object of the invention is to provide a toy of the type in which a figure mounted on a vehicle is made to simulate walking when the vehicle is moved forwardly.

A particular object of the invention is 15 to provide a toy in which a figure mounted on a vehicle is caused to go through the motions usually employed by a child in propelling such a vehicle.

A still further object of the invention is 20 to provide means for imparting a swinging movement to the entire leg of a figure in combination with means for swinging the lower limb forwardly when the leg is raised, whereby the foot is brought to the 25 floor with leg in its forward position and the lower limb is swung when the vehicle moves forwardly.

A construction designed to carry out the 30 invention together with other novel features of the invention will be hereinafter described.

The invention will be more readily understood from a reading of the following 35 specification and by reference to the accompanying drawings in which examples of the invention are shown and wherein:

Fig. 1 is a side elevation of a toy constructed in accordance with my invention,

Fig. 2 is a partial rear elevation of the 40 same,

Fig. 3 is a detail of the operating means,

Fig. 4 is a side elevation of a modified form,

Fig. 5 is a partial rear elevation of the 45 same, the figure being partially in section, and

Fig. 6 is an elevation of the modified operating means,

Fig. 7 is a detail of the knee joint and 50 limb swinging means.

In the drawings the numeral 10 indicates the platform or seat of a small vehicle having a pair of rear wheels 11 and a single front wheel 12 centrally thereof and journaled in the lower end of a steering post 55 13 which extends up through and supports

the front end of the seat. Such vehicles are popularly known as "kiddie" cars. It is to be understood that the invention may be applied to any type of toy or miniature 60 vehicle found suitable for the purpose and pleasing to the desires of children.

On the seat is mounted a figure which in the present instance is shown as the trunk 14 of the body of a child simulating the 65 position it would occupy in propelling such a vehicle. It is to be understood that the type of figure is immaterial and may assume any shape or representation desirable. On each side of the bottom of the trunk is 70 suitably pivoted the upper end of a leg 15, the upper member of which is disposed at a downward and forward inclination. The lower end of each leg 15 is bifurcated to receive a tenon 16 on the upper end of a 75 lower limb 17, said tenon being mounted on a transverse pivot pin 18 passing the same and the furcations. In this manner a knee-joint is formed.

A screw-eye 19 mounted on the upper 80 end of each tenon has fastened therein the lower end of an elastic cord or equivalent 20 which extends up the front of the leg and has its upper end fastened by a staple or other fastening 21. When the limb 17 85 is swung to its rear position as is shown in full lines in Fig. 1 the cord is placed under tension, so that when the limb is released it will be swung forwardly. A foot 22 is suitably pivoted to the lower end of 90 each limb and the sole may be provided with a roughened surface (not shown) so as to give traction upon the floor.

It will be seen that when the leg 15 is 95 swung forwardly it is raised and the limb 17 will be swung forwardly by the cord to the position indicated in dotted lines in Fig. 1. When the vehicle is moved forwardly the foot remaining in contact with the floor will cause the limb to swing and simulate the natural movement of a child in propelling the vehicle. Many devices 100 may be employed for swinging the legs. In Figs. 1 to 3 I have shown a detent 23 mounted on each side and suspended from the seat 10 by staples 24. The forward end of each detent is pivoted to the rear side of the leg 15 below its pivot point. The rear end of each detent has a depending arm 25 having its lower end bent forwardly to form 105 an angular finger 26. Each wheel 11 has a pin 27 on its inner side in position to engage 110

one of the fingers 26 and displace the arm forwardly, whereby the detent 24 is slid forwardly and the leg 15 swung. The pins 27 are placed diametrically opposite so as to 5 alternately swing the legs.

The form shown in Fig. 1 is supposed to be pulled or pushed by the child in playing with the toy. In Figs. 4 to 6 I have shown a spring motor 28 mounted in the trunk 14. 10 Oppositely bent crank arms 29 extend from the sides of the motor and are pivotally connected to the upper ends of links 30 which have their lower ends bent outwardly and connected with the legs 15 above the pivots 15 of the latter. A driving pulley 31 is also mounted on the side of the motor and supports the upper end of an endless belt 32 which drives a pulley 33 mounted on the shaft 11' which connects the rear wheels 11. 20 When the motor is released the links swing the legs and the belt drives the shaft, whereby the vehicle is propelled forwardly.

It will be seen that when the vehicle is moved forwardly in any manner, the legs 15 are alternately swung forwardly and raised, by the particular mechanism employed. When a leg is raised the cord 20 which is under tension will swing the limb 17 forwardly as shown in dotted lines in Figs. 30 1 and 4. When the limb 17 is swung for-

wardly the foot 22 being pivoted is balanced to swing in a manner simulating the motion of a human foot in such an action, which adds to the realistic appearance. When the limb 17 reaches the forward limit of its 35 swing the leg is lowered so that the foot 22 rests flat on the floor. As the vehicle moves forwardly the limb is swung upon its pivotal connections until it reaches the position shown in full lines. The alternate 40 movement of the legs gives a realistic imitation of walking.

The invention is presented as including all such changes and modifications as come 45 within the scope of the appended claim.

What I claim is:

In a toy of the character described, a horizontal platform seat, a wheel supporting the front end of the seat, a pair of wheels supporting the rear of the seat, a 50 figure having its trunk mounted on the seat, legs pivoted to the body and depending on each side of the seat, means mounted on the seat and engaging the legs for swinging the same, means on the rear wheels for sliding 55 said leg swinging means, lower limbs hinged to the legs, and elastic connections between the legs and the lower limbs.

In testimony whereof I affix my signature.
JOHN L. HENRY.
